UNITED STATES PATENT OFFICE.

CHARLES FALKENBERG, JACOB FALKENBERG, AND MORRIS JONES, OF NEW YORK, N. Y.

SHIRT.

SPECIFICATION forming part of Letters Patent No. 393,548, dated November 27, 1888.

Application filed July 24, 1888. Serial No. 280,877. (No model.)

To all whom it may concern:

Be it known that we, CHARLES FALKENBERG, JACOB FALKENBERG, and MORRIS JONES, of the city, county, and State of New York, have 5 invented a new and Improved Shirt, of which the following is a full, clear, and exact description.

Our invention relates to woolen shirts having attached collars which may be turned in 10 and a linen collar worn; and the object of the invention is such construction of the collar-band and attached collar that when the collar is turned in all uncomfortable fullness at the neck is avoided.

15 Reference is to be had to the accompanying drawings, forming a part of this specification, in which similar letters of reference indicate corresponding parts in all the figures.

Figure 1 is a perspective view of a shirt made 20 in accordance with our invention, the collar being shown upon the outside. Fig. 2 is a similar view showing the collar turned in, and Fig. 3 is an enlarged sectional view showing the construction of the neckband and collar.

25 The body A of the shirt may be of the usual or of any approved construction. The collar B is adapted to be worn upon the outside, as shown in Fig. 1, or turned in, as shown in Fig. 2, and a linen collar attached to the collar-band C. The lower edge of the collar B is stitched to the band C below the upper edge 30 of the band, so that a welt, a, is formed above the collar when the same is turned in. An inner thin strip of material, E, unites the upper edge of the body A to the lower edge of

the collar B. The neckband is folded in at its upper edge to form the said welt a, as shown at c. It is also folded in at its lower edge, as shown at c', a space, c², being left between the edges of the band, so that when the collar is 40 turned in, as in Fig. 2, the lower edge of the collar, by the elasticity of the fabric, drops into this space, and thus obviates the thickness which would otherwise be produced.

The collar B, outer neckband, C, and inner 45 band, E, are stitched together by a single seam, e, and the outer neckband and inner band are stitched to the body A of the shirt by a single seam, e'.

Having thus described our invention, what 50 we claim as new, and desire to secure by Letters Patent, is—

As an improved article of manufacture, a shirt having an outer neckband, C, turned in at its upper and lower edges, said edges being 55 separated from each other to form the space c², and the lower edge secured to the body of the shirt, in combination with the collar B, secured to the outer neckband, C, and the inner neckband, E, covering-space c², the edges 60 of the said band E being stitched to the body of the shirt and to the lower edge of the collar B and to the turned-in upper edge of the outer neckband, C, substantially as described.

CHAS. FALKENBERG.
JACOB FALKENBERG.
MORRIS JONES.
